UNITED STATES PATENT OFFICE.

SIDNEY J. FINN, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

MACHINE FOR TRIMMING RUBBER HEELS.

Application filed February 3, 1926. Serial No. 85,718.

This invention relates to trimming machines and is herein illustrated as embodied in a machine designed to trim the overflow from rubber heels for boots and shoes.

5 To those familiar with the molding of rubber heels it is known that the plates and the cavity member of a heel mold are rarely if ever fitted so accurately as to prevent overflow of the rubber. Thus, overflow commonly occurs both at the tread surface and at the attaching surface, and at the breast of the heel as well as around the periphery.

A preferred style of rubber heel for rubber boots differs from other rubber heels in 15 that it is molded with a thin, flexible lip formed on and projecting from the breast as an extension of the attaching surface. Such a lip, by reason of its flexibility, is adapted to conform readily to the transverse 20 or other curvature of the shank of the boot, and when properly vulcanized to the shank it provides a more satisfactory joint between the heel and the boot than would be formed if the heel had no lip. On the other hand, the 25 provision of a lip introduces an additional trimming problem, since it is necessary to trim off whatever overflow is formed on the forward edge of the lip and at the same time to preserve the lip for its intended purpose.

30 To this end a feature of the invention consists in an improved organization comprising trimming means and a work-guiding member arranged to clear a lip such as that described and to engage the surface from 35 which the lip projects. The work-guiding member is thus arranged to maintain the aforesaid surface at a suitable distance from the trimming means to preserve the lip from being cut by the trimming means while the 40 overflow is being trimmed from the lip.

It is desirable that an overflow-trimming machine should be usable not only to trim the overflow from a lip as aforesaid, but also to trim the overflow from other parts 45 of the heel. Accordingly, in the illustrated machine the work-guiding member is arranged to be adjustable toward and from the trimming means and is so shaped and arranged that when adjusted as closely as possible to the trimming means the machine 50 may be used to trim off the overflow flush with the body of the heel around the periphery and at the junction of the breast and

tread surfaces. Furthermore, if the heel has no lip such as that hereinbefore described 55 the machine is usable to trim the overflow from the junction of the breast and the attaching surface.

Many operatives prefer a machine equipped with a work table, particularly 60 when they use the machine to trim the overflow from the periphery of the heel. When the latter operation is being performed it is necessary to turn the heel, and the work table not only helps to speed production but 65 it helps to make the trimming uniform. The work table is also desirable when trimming the overflow from a lip formed on the breast. It is preferably mounted to tilt about a horizontal axis so that the plane of 70 the work-supporting surface may be inclined more or less relatively to the trimming means to facilitate close trimming. Prior machines have been provided with work tables adapted to be tilted in this manner and a handle 75 has been attached to the work table in such a position that the operative, while manipulating the heel with the right hand, could manipulate the handle with the left hand to adjust the work table to the desired angle. 80 Now, however, since an overflow trimming machine, to be universally adaptable to trim all parts of all styles of heels, requires adjustment of the work-guiding member to one 85 position when trimming the overflow from a lip and to another position when trimming the overflow flush with the body of the heel, the problem of adjusting both the work table and the work-guiding member arises, and consequently a further object of the invention is to provide convenient means by 90 which the operative may effect both of these adjustments individually or collectively without substantially retarding production, to the end that a heel, whether it has a lip 95 or not, may be wholly trimmed with one handling.

Accordingly, another feature of the invention consists in a manually movably adjusting member and connections arranged to 100 communicate movement thereof to the work-guiding member, whereby the latter may be adjusted in accordance with the requirements of the operation to be performed. The said manually movable member is also 105 preferably connected to the work table so

that it may be used to tilt the latter to the desired angle of inclination. To utilize said manually movable member to effect adjustments of the work-guiding member and the work-supporting table each independently of the other, the connections by which its motions are communicated, as illustrated, are such that movement of one kind is communicated exclusively to the work-guiding member while movement of another kind is communicated exclusively to the work table. Consequently, by suitably controlling the movements of the manually movable member the latter may be used to maintain either one of the adjustable work-engaging members in any desired position while it is being moved to alter the adjustment of the other one of said work-engaging members.

Still another object of the invention is to provide improved means for feeding the work relatively to the trimming means. Accordingly, the illustrated feeding means comprises the aforesaid work-guiding member which is preferably a rotary disk having a substantially flat marginal work-engaging surface. This disk is driven by suitable transmission means and its work-engaging surface, being flat, is adapted to have a considerable area of contact with flat surfaces such as straight breasts and is also adapted to have a considerable area of contact with convex surfaces such as the peripheries of heels. Inasmuch as the plane of this flat, work-engaging surface is at right angles to the axis of rotation, the aforesaid adjustment of the work-guiding member may be readily effected by shifting it lengthwise of its axis. Other features of the invention are hereinafter described and claimed and are illustrated by the accompanying drawings.

Referring to the drawings:

Fig. 1 is a perspective view of a portion of an overflow trimming machine organized in accordance with this invention;

Figs. 2 and 3 are perspective views of a rubber-boot heel before and after being trimmed;

Fig. 4 is a vertical section through a portion of the machine and shows a rubber-boot heel in position to have the overflow trimmed from the lip;

Fig. 5 is a top plan view, partly in section, of a suitable form of means for communicating adjusting movement from a manually movable member to the work-guiding member; and

Fig. 6 is a view similar to Fig. 4 showing another style of heel and a correspondingly different adjustment of the work-guiding member.

In various respects the general organization of the illustrated overflow trimming machine is like that disclosed in United States Letters Patent No. 1,534,257, granted April 21, 1925, upon application of James

A. Brogan, and reference may be had to said Letters Patent for a more complete disclosure of the construction and operation of parts not fully described herein.

The illustrated machine comprises a main frame 10 having suitable bearings for two driven cutter-shafts 12, 14 and other parts to be described. Rotary shearing cutters 16, 18 are attached respectively to the said shafts and are arranged to lap one another slightly, as shown in Figs. 4 and 6. Their directions of rotation are indicated by arrows in Fig. 4. A work-supporting table 20 is mounted on horizontal trunnions 22, and a handle 24 is connected to the table for the purpose of tilting the latter about the axis of said trunnions to vary the angle of inclination of the work-engaging surface of the table. Ears 26 are formed on the table and the handle 24 is pivoted thereto by a screw 28.

The work is guided relatively to the cutters by a substantially flat work-engaging surface 32 formed on the margin of a rotary disk 30. This disk is attached by a screw 34 to a shaft or stem 36 journaled in a suitable bearing formed in a bracket 38. The shaft 36 is provided with a pulley 40 to be driven by a belt 42. As shown, the belt passes over idle pulleys 44 and is driven by a pulley (not shown) on the cutter shaft 12. Since close trimming on the body of the heel requires inclining the heel to counteract the thickness of the guiding member 30 (see Fig. 6) the back of the latter is beveled to a thin edge and the axis thereof is correspondingly inclined to take advantage of the bevel and to make the lines of adjusting movement substantially parallel to the average plane of the work-supporting table.

The work-guiding member 30 is normally urged toward the cutter 18 by a compression spring 46 arranged in a socket in the bracket 38 and bearing against a head 48 formed on a screw carried by the stem 36. The stem is provided with an internal screw-thread to engage the member 48 so that the latter may be adjusted to various positions relatively to the stem. The head 48 is preferably cone-shaped to have line contact with a cam surface 50 formed on a slide 52 (Fig. 5). A portion 56 of the bracket 38 engages a flat surface 54 of the slide to sustain the thrust of the spring 46. The bracket is bored to provide a bearing 58 in which a stem 60 of the slide 52 is arranged. The range of movement of the member 52 may be regulated by two adjustable stops 62 and 64, the stop 62 being a nut screwed on one end of the stem 60, and the stop 64 being a screw extending through a portion of the member 52. A compression spring 66 surrounding the stem 60 normally shifts the slide 52 in one direction as far as the stop 62 will permit, the cam surface 50 thereby

permitting the guiding and feeding disk 30 to approach closely to the cutter 18, as shown by Figs. 5 and 6. When the slide 52 is shifted in the opposite direction, the cam surface 50 shifts the guiding and feeding member 30 away from the cutter 18 to the position shown by Fig. 4, this position being variable and determined by adjustment of the stop-screw 64 which abuts against the stationary bracket 38.

To enable the operative to shift the work-guiding and feeding member 30 by the same handle that is provided to tilt the work-supporting table 20, said handle is provided with an operating finger 68 and the slide 52 is provided with a member 70 arranged to be engaged by said finger. The effective surface of the member 70 extends at right angles to the axis of the trunnions 22 to render the tilting of the work-supporting table 20 and the corresponding movement of the handle 24 of no effect with respect to the position of the guiding and feeding member 30. On the other hand, movement of the handle 24 about its pivot 28 is effective to shift the work-guiding and feeding member 30, but this kind of movement of the handle has no effect with respect to the inclination of the work-supporting table 20. If it were desired to shift both the members 20 and 30 simultaneously it could be accomplished by a compound movement of the handle 24 including a component of movement about the axis of the trunnions 22 and a component of movement about the pivot member 28. Thus, the handle 24 is adapted to adjust either the member 20 or the member 30 or both, as the case may be, according to the will of the operative.

The piece of work shown in Fig. 3 represents a rubber-boot heel after all the overflow has been trimmed therefrom. The same heel, before being trimmed, is shown by Fig. 2. The body of the heel has a tread surface 72, a periphery 74, a breast 76 and a concave attaching surface 78. A thin flexible lip 80 is formed on the breast as an extension of the attaching surface 78. In the molding of such a heel it usually happens that an overflow formation 82 projects from the junction of the periphery and the tread surface and from the junction of the breast and tread surface. A corresponding fin 84 of overflow commonly projects from the junction of the periphery and the attaching face 78, and since a heel of this style has a lip 80 it usually happens that a fin 86 of overflow is formed thereon.

To trim the overflow from a heel such as that shown by Fig. 2, the preferred method of procedure is to trim off the overflow 82 and thereafter trim off the overflow 84 and 86. To follow this procedure the tread surface 72 would be placed on the table 20 and the guiding and feeding member 30 would

be adjusted close to the cutter 18, as shown by Fig. 6. Assuming that the periphery 74 is the first surface to be trimmed, it would be held in contact with the flat face 32 of the member 30. The junction of the tread and periphery would thus be brought into tangential relation to the cutters, the tilting of the table 20 being instrumental in regulating, within narrow limits, the closeness of trimming. By manipulating the handle 24 with the left hand and the heel with the right hand the operative may work rapidly, since the feeding of the work is accomplished by the rotation of the member 30 in the direction indicated by an arrow on the stem 36 in Fig. 4. Having traversed the periphery 74, the breast 76 may be placed in contact with the member 30 to trim the overflow from the junction of the tread and breast. Then, inverting the heel, the operative will place the attaching face on the table 20 and will proceed as before to trim the overflow 84 from the junction of the attaching face and the periphery. It remains now merely to trim the overflow 86 from the lip 80, and the operative will first remove the handle 24 about the pivot 28 to shift the member 30 away from the cutters to the position shown by Fig. 4. It is to be assumed that the stop screw 64 has been adjusted according to the width of the lip 80 so that when the outward movement of the guiding member 30 is arrested thereby the member 30 will maintain the breast of the heel spaced a suitable distance from the cutter 18, as shown by Fig. 4. The member 30 is also spaced a suitable distance above the table 20 to clear the lip 80, and the trimming may therefore proceed without hindrance. The guiding member 30

functions by engagement with the body of the heel when the machine is used to trim the overflow 86 from the lip 80 as well as when it is used to trim the overflow flush with the body of the heel.

A heel such as that illustrated in Fig. 6 has no lip and may therefore be trimmed without separating the member 30 from the cutter 18. This heel is a typical example of a heel designed to be attached to a walking shoe. The tread is indicated at 88, the periphery at 90, the attaching surface at 92 and the breast at 94. All the overflow 96 may be trimmed from the heel of this style while the guiding and feeding member 30 remains in contiguous relation to the cutter 18, and when large numbers require trimming it is sometimes expedient to handle each heel twice, since many operatives become so expert that they prefer to work without the table 20 when trimming the breast. Consequently, it is common to trim the overflow from the periphery while the table 20 is attached, and when a lot of heels has been handled for this operation, the work table may be detached and the heels may be han-

- dled again to trim the overflow from the breast at both the tread 88 and the attaching surface 92. The latter operation is represented by Fig. 6.
5. The foregoing examples of work illustrate the universal adaptability of the illustrated machine to trim all overflow from all styles of rubber and rubber composition heels.
10. Having thus described my invention, what I claim as new and desire to secure by Letters Patent of the United States is:
1. A machine for trimming the overflow from rubber heels, comprising trimming means, and a work-guiding member arranged to clear a lip formed on a surface of a heel and to engage said surface to space it from said means while the latter trims the overflow from said lip.
  20. 2. A machine for trimming the overflow from rubber heels, comprising trimming means, and a rotary disk having a substantially flat marginal portion arranged to clear a lip formed on the body of a heel and to engage said body to space it from said means while the latter trims the overflow from said lip.
  30. 3. A machine for trimming the overflow from rubber heels, comprising trimming means, and a rotary driven member having a substantially flat surface arranged to engage the body of a heel to feed the latter and to guide it while said means trims the overflow therefrom.
  35. 4. A machine for trimming the overflow from rubber heels, comprising trimming means, and a rotary driven disk having a thin and substantially flat marginal portion arranged to engage the body of the heel to feed and guide the latter while said means trims the overflow therefrom, said disk being adjustable lengthwise of its axis to regulate the closeness of trimming.
  40. 5. A machine for trimming the overflow from molded rubber articles comprising rotary shearing cutters and means for driving them, a work-engaging table relatively to which an article of work may be fed in cooperative relation to said cutters, a rotary disk the marginal portion of which is in lapped relation to one of the said cutters and is provided with a flat work-engaging face, and means for driving said disk to feed an article of work held manually against said flat face.
  45. 6. A machine for trimming the overflow from molded rubber articles, comprising rotary shearing cutters and means for driving them, a rotary disk the marginal portion of which is arranged in lapped confronting relation to one of said cutters to engage and guide the article, and means for driving said disk to feed the article, said disk being adjustable lengthwise of its axis to regulate the closeness of trimming.
  7. A trimming machine comprising a rotary trimming cutter, and a rotary driven work-feeding disk arranged in lapped relation to said cutter, one side of said disk having a substantially flat work-engaging surface and the opposite side having a beveled marginal face confronting said cutter, the axis of said disk and the axis of said cutter being at an angle to counteract the angle of said beveled face.
  75. 8. A machine for trimming the overflow from molded rubber articles, comprising trimming means, a work-engaging member arranged to control the closeness of trimming, said member being adjustable to regulate the closeness of trimming, a spring arranged to adjust said member in one direction, and manually operative means arranged to adjust it in the opposite direction.
  80. 9. A machine for trimming the overflow from molded rubber articles, comprising trimming means, work-feeding mechanism including a rotary driven work-engaging member arranged to be adjustable axially to regulate the closeness of trimming, a manually operative controller, and means arranged to communicate movement of said controller to adjust said work-engaging member axially.
  85. 10. A machine for trimming the overflow from molded rubber articles, comprising trimming means, an adjustable work-supporting table, an adjustable work-guiding member arranged to control the closeness of trimming, a manually operative adjusting member arranged to adjust said table, and means arranged to communicate movement from the latter said member to adjust said work-guiding member.
  90. 11. A machine for trimming the overflow from molded rubber articles, comprising trimming means, an angularly adjustable work-supporting table, an adjustable work-guiding member arranged to control the closeness of trimming, a manually operative adjusting member, and connections arranged to communicate adjusting movements to said table and to said guiding member from said adjusting member.
  95. 12. A machine for trimming the overflow from molded rubber articles, comprising trimming means, an adjustable work-supporting table, an adjustable work-guiding member arranged to control the closeness of trimming, and an adjusting member movable in one direction to adjust said table and in another direction to adjust said guiding member.
  100. 13. A machine for trimming the overflow from molded rubber articles, comprising trimming means, an adjustable work-supporting table, an adjustable work-guiding member arranged to control the closeness of trimming, and an adjusting member movable about one axis to adjust said table and about

another axis to adjust said guiding member. operative means arranged to shift said shaft axially to regulate the closeness of trimming, and a stop arranged to limit the adjusting movement of said disk in one direction.

14. A trimming machine comprising a rotary trimming cutter, a rotary disk the marginal portion of which is arranged in 10 lapped confronting relation to said cutter to. In testimony whereof I have signed my 5 guide the work, a driven shaft to which said name to this specification.

SIDNEY J. FINN.
